UNITED STATES PATENT OFFICE

EDWARD L. IRSIK, OF INGALLS, KANSAS

RAILROAD-CROSSING GATE

Application filed April 15, 1929. Serial No. 355,321.

The present invention appertains to improvements in railroad crossing gates and more particularly to a gate of the type operated by the rolling stock.

5 The principal object of this invention is to provide a railroad crossing gate which will be entirely automatic in operation.

Another important object of the invention is to provide a crossing gate which, in operation will be positive acting and which, because of its simple construction, will not readily develop defects.

These and other very important objects of the invention will become more apparent to 15 the reader after considering the invention as described and claimed hereinafter.

In the drawings:

Figure 1 represents a top plan view of a railroad crossing showing the roadway and 20 track equipped with the improved mechanism.

Figure 2 represents a longitudinal sectional view through one of the gate structures.

Figure 3 represents a transverse sectional 25 view through the said gate.

Figure 4 represents a side elevation of the operator and fragmentarily showing the buffer of a locomotive, with means engageable therewith.

30 Figure 5 represents a side elevation of the catch release, the same showing the opposite side from that shown in Figure 4.

Referring to the drawings, wherein like numerals designate like parts, at each side of 35 the track rails 5—5 and extending transversely of the roadway 6 is a gate mechanism generally referred to by numeral 7. Each gate construction consists of an elongated housing 8, provided with a removable top cover 9, 40 which is adapted to lie substantially flush with the surface of the roadway 6. The plate 9 is formed with the longitudinally extending slot 10, while a bar 11 is supported at its ends by the end walls of the housing 8 and is located slightly beneath the top plate 9. To the bar 11 are pivotally connected 45 fingers 12, which are pointed at their upper ends and allowed to protrude through the slot 10 when in upright position. These figures 50 are pivotally connected to the bar 11 as

at 13 and at their pivotal ends, the fingers 12 are provided with obliquely disposed stems 14. A slideable rod 15 is slidably disposed through an opening 16 in one end of the housing and has pivotally connected thereto the free ends of the stem 14. A lug 17 depends from the rod 15 and has an offset portion 18, adapted to be engaged by the head 19 of a rockable catch member 20.

55 A rod 21 is pivotally connected as at 22 to the opposite end of the rockable member 20 and extends through an opening 23 in the opposite end wall of the housing 8. A coiled spring of the expansible type is designated by numeral 24, and tends to normally maintain 60 the fingers 12 in retracted position.

65 The bar 15 connects to the rocker 25. A connecting link 26 extends between the rocker 25 and a second rocker 27, while a rod 28 is pivotally connected at one end to the rocker 27 and at its opposite end to the lower end of a vertically disposed rockable lever 29, which is adapted to be engaged by the arcuate arm 30 on the front of the locomotive generally referred to by A. The rockable lever 29 is 70 mounted upon a suitable upright 30 in the manner as shown in Figure 4.

75 The rod 21 is connected to a cable 31 which is trained over a pulley 32 and led to the lower end of a rockable lever 33, mounted upon a 80 suitable support 34 for a rocking motion on a plane transverse to the track rails 5—5, whereas the lever 29 rocks on a plane parallel to the rails 5—5. It will thus be seen that when the arcuate arm 30 engages the lever 29, 85 the movement of the lever will move the fingers 12 into the position shown in Figure 2. The lug 17 will have its offset 18 engage the head 19 of the catch 20 and thus retain the fingers in upright position even though the 90 lever 29 is released. The arm 30 will afterward engage the rockable lever 33 and move the outer end thereof outwardly so that the lower end thereof will exert a pull on the cable 31 to release the rockable catch 20 and 95 permit the fingers 12 to retract.

The mechanism has been shown in duplicate so as to operate the gate by a train moving in either direction.

100 While the foregoing description has been

in definite terms, it is to be understood that various changes in the specific shape, size and materials may be resorted to, without departing from the spirit or scope of the invention as claimed hereinafter.

5 Having described the invention, what is claimed as new is:

A railroad crossing gate comprising a housing embedded in a roadway, a plurality of 10 pivotally mounted and normally concealed members arranged within the housing, track means for elevating the said members to protrude upwardly from the housing when engaged by rolling stock, latch means for retaining the pivotal members in elevated position after the rolling stock has released the 15 said track mechanism, additional track mechanism for releasing said retaining means after the rolling stock has passed the roadway, and spring means for retracting the pivotal members.

In testimony whereof I affix my signature.
EDWARD L. IRSIK.
